UNITED STATES PATENT OFFICE.

HOWARD I. MORRIS, OF LOS ANGELES, CALIFORNIA, ASSIGNOR, BY DIRECT AND MESNE ASSIGNMENTS, TO MORRIS TIRE MACHINERY COMPANY, OF LOS ANGELES, CALIFORNIA, A CORPORATION OF CALIFORNIA.

BIAS-FABRIC MACHINE.

1,359,092.

Specification of Letters Patent. Patented Nov. 16, 1920.

Application filed February 21, 1918. Serial No. 218,485.

To all whom it may concern:

Be it known that I, HOWARD I. MORRIS, a citizen of the United States, residing at Los Angeles, in the county of Los Angeles, State of California, have invented a new and useful Bias-Fabric Machine, of which the following is a specification.

This invention relates to the art of weaving fabric and has for its general object the provision of automatic mechanism for producing bias fabric, that is to say, fabric in which the threads run diagonally across the fabric from side to side.

A further object of the invention is to provide an automatic mechanism by which tubular bias fabric may be produced.

A further object is to provide automatic mechanism by which flat bias fabric may be produced.

A further object of the invention is to provide a construction and interrelation of the mesh-forming mechanism proper which shall be compact, accessible and positive in action requiring a minimum of attention; also to provide suitable mechanism for compacting the mesh of the fabric after the same has been formed by the weaving mechanism proper; to provide suitable tension or holding mechanism for holding the fabric as it is being formed and to provide suitable feeding mechanism for feeding the fabric along after the meshes thereof have been compacted.

Another object of the invention is to provide simple and efficient mechanism by which bias fabric may be produced with suitable selvage edges or sides.

Further objects of the invention will hereinafter appear in connection with the detailed description of an embodiment thereof.

In the accompanying drawings I have illustrated a construction of preferred form of machine embodying my invention, and in these drawings:

Figure 1 is a side elevation, portions being broken away to more clearly illustrate the construction and interrelation of parts, this elevation being taken at right angles to the axis of the main cam shaft.

Fig. 2 is a vertical section taken on a line at right angles to the cam shaft and looking in a direction parallel to the axis of the cam shaft; the position of the parts being that assumed when the frames have been oscil-

lated approximately one-half their movements. 55

Fig. 3 is a partial vertical section showing more particularly the shuttle tubes or carriers, hooks, comb and feeding mechanism. 60

Fig. 4 is a partial plan view of a section of the upper frame showing the shuttle tubes or carriers and the reverse mechanism.

Fig. 5 is a partial vertical section of the reverse mechanism. 65

Fig. 6 is a diagram of the successive operations of the shuttle tubes or carriers when producing tubular bias fabric.

Fig. 7 is a diagram of the successive operations of the shuttle tubes when producing flat bias fabric and illustrating the reversal of tubes at the selvage and the manner in which the tubes surround the selvage cord. 70

Figs. 8, 9 and 10 are diagrammatic views illustrating the manner in which the fabric is formed and the mesh of the fabric driven up by the comb. 75

Fig. 11 illustrates the insertion of longitudinal cords in the fabric. 80

Fig. 12 illustrates a single cord fabric.

Fig. 13 illustrates a two-cord fabric.

Fig. 14 illustrates a four-cord fabric.

Fig. 15 is a side view of the mechanism for winding up the completed fabric. 85

Fig. 16 is an end view thereof.

Fig. 17 is a detail illustrating a means for holding the winding-up roll in place.

Fig. 18 is a diagrammatic view of the cam lay-out.

Fig. 19 is a side view of the cam for operating the hook of the reverse mechanism, the connecting parts operated by this cam being shown in dotted lines. 90

Fig. 20 is a top plan view.

Fig. 21 is a partial plan view of the reverse mechanism illustrating the construction and arrangement when the machine is adapted and adjusted to weave four-cord fabric. 95

Fig. 22 is a sectional view on the line $x^{22}-x^{22}$ of Fig. 3. 100

Fig. 23 is a sectional view on the line $x^{23}-x^{23}$ of Fig. 3.

Fig. 24 is a section on the line $x^{24}-x^{24}$ of Fig. 2 and shows the cam shafts and cam mechanism. 105

Fig. 25 is a sectional view through the cam shafts and cams.

Fig. 26 is a sectional view on the line x^{26} — x^{26} of Fig. 3.

In the embodiment of the invention illustrated in these drawings, the machine is shown as composed of an upper frame 1 and a lower frame 2 so constructed and supported from the main frame 3 of the machine that the frames 1 and 2 respectively may be oscillated about tubular stationary shafts 4 and 5.

The lower frame 2 is shown composed of three separate parts 6, 7 and 8. These parts are so arranged that they may not only be oscillated about the tubular shaft 5 but the parts 6 and 7 may be vertically reciprocated, the frame 6 being slidably mounted on the central hub portion 8' of the part 8 and the part 7 being slidably mounted on the vertical cylindrical extension 9 of the frame 6. This vertical reciprocating motion is imparted to the parts or frames 6 and 7 by means of the cam 10, levers 11 and 12, connecting rods 13, wing levers 14, and connecting rods 15 and 16. The wing levers 14 are fulcrumed on the hub of the frame 8, (Fig. 2). The connecting rods 16 are connected to the levers 14 to a point midway between the fulcrum and the point at which the connecting rods 15 are connected to the levers 14. It will thus be seen that as the wing levers 14 are raised by the connecting rods 13 by means of the levers 11 and 12 and cam 10 the connecting rods 15 will raise the frame 6 substantially twice as rapidly and also twice the distance that the connecting rods 16 raise the frame 7.

Each frame 1 and 2 carries a series of inner and a series of outer hooks 17. The respective series are arranged in concentric circles about such frame so as to form radial pairs. The frame 1 is provided with a series of slots 22, in which the outer series of hooks 17 are pivotally mounted, and with a series of ribs 22' forming slots in which the inner series of hooks 17 are pivotally mounted. The respective outer upper flanges or rims of the parts 6 and 7 of the frame 2 are provided with a series of slots as indicated at 6' and 7' in Fig. 3 and the respective hooks 17 pivotally mounted therein. These hooks 17 are adapted to engage projecting pins on the shuttle tubes or cord carriers 18. The hooks 17 on the upper frame 1 are mechanically operated by an oscillating ring 19 through connecting rods 20. The hooks 17 of the lower frame 2 are mounted on the parts 6 and 7 respectively and are under the constant tension of springs 21 which serve to normally hold the said hooks in hooked-up position.

When the lower frame parts 6 and 7 reach their upper positions, as shown in dotted lines in Fig. 3, if the hooks 17 carried thereby have brought up a shuttle tube such tube 65 is discharged therefrom and taken up by

the corresponding pair of hooks 17 of the frame 1, the positive actuation of the latter releasing the former. If, however, such shuttle tube were carried by the upper hooks 17 and the latter were actuated to release 70 the same, the tension of the springs 21 automatically causes the hooks 17 on the parts 6 and 7 to engage the pins of such shuttle tubes as the same are released by the upper hooks.

25 and 26 represent plates mounted, respectively, on the frame 1 and on the part 8 of the frame 2. These plates are annular in form extending horizontally substantially around the frames 1 and 8. Vertically 80 these plates are curved to correspond with the arc of a circle concentric with the top edge of the tube or shaft 5 and are each provided with a series of vertical slots (shown most clearly in Fig. 1 wherein portions are 85 broken away to show the plate 26 slotted vertically). As shown in Figs. 3, 4 and 5 the enlarged outer portions of the shuttle tubes are provided with grooves or channels 18' into which the walls of such slots in the 90 plates 25 and 26 are adapted to rest forming guides or tracks so that as the outer ends of the shuttle tubes 18 are moved upwardly and downwardly by the frame part 6 they are guided or 95 caused to travel in the arc of such circle. The adjoining edges of the plates 25 and 26 are arranged in sufficient close proximity to insure the passage of the shuttle tubes 18 from the slot in one plate to the registering 10: slot or track in the other. The inner ends or tips of the shuttle tubes 18 are thus maintained at a uniform distance from the edge of the tube 5.

The vertical movement of the frame 6 10: being substantially twice that of the frame 7, the shuttle tubes 18 as they are moved up and down are maintained in their radial position with respect to the hollow shaft or tube 5 with the inner ends thereof at practically a constant distance therefrom, the movement of such tubes being bodily upward or downward with the outer portions thereof moving more rapidly and through greater arcs of a circle than the inner ends 11: or inner portions thereof, and it is in the space intervening between the inner ends or tips of the shuttle tubes 18 and the edges of the tube 5 that the fabric is formed.

The shuttle tubes 18 carry on their outer 120 ends one or more spools 23 containing the cord, thread or yarn of which the fabric is to be formed. This cord or yarn passes from the spool or spools directly through the tube and is discharged from the tip end thereof. A constant tension is maintained on the cord by means of drag springs 24 (see dotted lines Fig. 3) which press directly upon the cord wound on the spool exerting resistance to the unwinding of the cord.

The frames 1 and 2 always oscillate in opposite directions. This oscillation is produced through the action of the cam 27, lever 28, connecting rod 29, lever 30, shaft 31, levers 32 and 33 and connecting rods 34, 34'. The upper rod 34 connects with an arm 34' carried on the upper frame 1 and the lower connecting rod 34 connects with an arm 34' (Fig. 2) on the part 8 of the lower frame 2. The levers 32 and 33 are set in opposed order on the shaft 31, thereby causing the oscillation of the frames 1 and 2 to be in directions opposite to each other. As the cam 27 produces a reciprocating movement of the lever 28 it will be seen that such reciprocation will cause each of the frames 1 and 2 to be oscillated back and forth and that when the frame 1 is oscillated to the right the lower frame 2 is oscillated 20 to the left and vice versa.

The amount of oscillation of the frames 1 and 2 is fixed in accordance with the adjustment of the connecting rod 29 on the boss 28' of the lever 28 and of the other end of such rod 29 on the lever 30. In the position shown in Fig. 24 the amount of such oscillation is equal to three slots or tracks. In the operation of the machine for a single cord fabric the rod 29 would have its inner end connected in the first position indicated by the opening near the fulcrum of the lever 28. This connection between the rod 29 and the lever 28 may be made by providing studs on the boss 28' and forming an opening in the end of the arm 29 or the end of the arm 29 may carry a stud or pin and the boss 28' be provided with a series of openings corresponding to the different positions. Similarly the connection between the rod 29 and lever 30 is by stud or pin, on the lever 30, adapted to receive the eye formed in the end of the rod 29. In Fig. 24 the lever 30 is provided with two such studs or pins, one at or near its end,--the other at its center. The rod may be mounted on either of these. Assuming that the connecting rod 29 is in this first position the amount of oscillation of the frames 1 and 2, respectively, will each be equal to one slot or track in the plates 25 and 26. Inasmuch as the frame 1 oscillates one slot or track to the right while the frame 2 is oscillating one slot or track to the left, it is obvious that each oscillation makes a difference of two slots in the 55 registration of the slots of the respective plates; that the movement of the plates upon such oscillation with respect to each other is equal to two slots or tracks and that at the end of such oscillation a given slot or track 60 in plate 25 has been brought into registration with the slot or track in plate 26 which, prior to such oscillation, was two spaces or slots to the side of such given slot. The return oscillation brings the slots into the 65 original registration.

The shuttle tubes or carriers are operated in two series. When a single cord fabric is to be produced these series are alternately arranged so that the two respective series would be made up of the respective odd and even numbered tubes or carriers. When tubular fabric is produced one of these series is progressively moved around the machine in one given direction while the other series is progressively moved around in the opposite direction. The series are alternately raised and lowered with each oscillation, thereby braiding or interweaving the cords as the tubes are passed about each other. This operation may be explained in detail 80 as follows:—Assume the shuttle tubes of the series which is moving to the right to be in the upper frame, (the series of shuttle tubes moving to the left at this time will be carried by the lower frame). When the upper 85 frame has been oscillated to the right this right hand moving series is then transferred to the lower frame which on the next or return oscillation of the lower frame moves to the right. The left hand moving series 90 has simultaneously been transferred to the upper frame, which, upon such succeeding or return oscillation, moves to the left. It is thus seen that by this step by step motion the respective series are progressively advanced in their given direction alternating between the upper and lower frames as the oscillation thereof corresponds to the direction of such series.

The arrangement of the tubes or carriers 100 18 in this operation is such that every alternate slot of the plate 25 and also every alternate slot of the lower plate 26 is vacant during the oscillating movement so that when the oscillation has been stopped at either 105 end of the movement the empty slots of the plate 25 register with the occupied slots of the plate 26 and vice versa.

It is obvious that where tubular fabric is to be produced there must be an even number of slots in the plate 25 and the same even number in the plate 26 and that the slots occupied by the series of tubes traveling in one direction are at no time occupied by any of the series of tubes traveling in 115 the other direction. It is also obvious that the total number of slots in either plate 25 or plate 26 corresponds to the total number of tubes or carriers in the machine.

The outer series of hooks 17 of the upper 120 frame have extensions 58 to which the connecting rods 20 are attached. In turn these outer hooks 17 are respectively connected in pairs with the inner hooks 17 of the upper frame by rods 59 so that the respective 125 hooks 17 of the upper frame are mechanically operated in pairs. The outer series of hooks 17 of the upper frame is operatively divided into two separate and distinct series so that the even numbered hooks are ac- 130

tuated to release the tubes or carriers thereby carried and permit the same to be engaged by the hooks of the lower frame while the alternate or odd numbered hooks 5 of the outer series of the upper frame are mechanically actuated to displace the hooks 17 of the lower frame and engage the pins of the tubes or carriers 18 in the slots of the ring, and vice versa. The ring 19 is provided with two projecting flanges, one above the other; each of which is provided with a series of holes to receive the hooked ends of the connecting rods 20 (see particularly Fig. 3). The connecting rods 20 of one series 15 of hooks 17 of the upper frame are connected to the upper ring 19 and the connecting rods 20 of the other set of such hooks are connected to the lower ring 19. These connecting rods are so arranged that when the 20 ring 19 has been oscillated to its limit in one direction, one set of connecting rods 20 will stand in radial position with respect to the ring 19 and the hooks of that set will be actuated to unhook from the shuttle 25 tubes while the other set of connecting rods 20 will stand at an angle and the hooks of that set will be thereby actuated to hook up on the shuttle tubes. Upon the oscillation of the ring 19 to its opposite position 30 this action is reversed.

Assuming that the lower frame 2 has been raised to its upper position all of the shuttle tubes will be in their upper positions. It is while the tubes are all in this 35 position that one series of the hooks 17 on the frame 1 are actuated so as to hook onto one set or series of shuttle tubes and the other series of hooks 17 actuated to be released from the second series, permitting 40 the hooks 17 of the lower frame 2 to automatically engage said second series.

The ring 19 is oscillated by means of the cam 48 (Figs. 1 and 24), levers 49 and 50, connecting rod 51, bell crank 52, connecting rod 53, levers 54 and 54', connecting rods 55 (Figs. 1 and 2) and bell cranks 56 which carry teeth between which a tooth 57 on the ring 19 engages. A shaft 54² extends through a central hub of the lever 54, 50 which is keyed thereon, over to the lever 54' also keyed upon said shaft.

The movement in one direction of the shuttle tubes supported by the upper frame and in the opposite direction of the shuttle 55 tubes supported by the lower frame carries these tubes past one another, thereby causing the cords or yarn to be crossed. These crosses are then driven or pushed down to a tight or compact formation adjacent to 60 the edge of the tube 5 by the action of a comb 60. This comb is made up of a series of radially disposed thin blades so arranged that a downward movement thereof will insert the tips of the blades immediately behind the points of crossing of the

cords and the further downward movement of the blades will wedge or push the crossed portions of the cords toward the edge of the tube 5, as shown most clearly in Fig. 2, as the comb blades have an inner face or edge 70 which is inclined upwardly and inwardly.

The comb 60 is positively operated upward and downward by means of the cam 61, levers 62 and 63, connecting rod 64, lever 65 and connecting rods 66.

75

Figs. 8, 9 and 10 illustrate diagrammatically the action of the interweaving or braiding of the cords causing the formation of the crosses, and the action of the comb 60. In Fig. 8 the shuttle tubes 18 are represented as all in their upper position, to wit, in the plate 25 of the upper frame. At this time the completed section of fabric represented at 67 is within the tube 5 immediately below the upper edge thereof and the cords extend radially with respect to the vertical axis of the machine from the edge of the tube 5 to the shuttle tubes 18.

In Fig. 9 the frames 1 and 2 having been 90 oscillated and all the tubes or carriers 18 again brought to the upper position, the cords are crossed in front of the tips of the carriers and the tips of the blades of the comb 60 illustrated as just entering behind 95 the crosses.

In Fig. 10 the comb has completed its downward movement and the crosses have been forced over the edge of the tube 5 closing up the mesh of the fabric. The action 100 of the comb blades alone would not force the crossed portions beyond the edge of the tube 5. This is accomplished by the combined action of the comb and the feeding element.

105

As the respective series of shuttle tubes are carried alternately in the upper and lower positions and oscillated past each other it is obvious that a given cord alternately passes over or on top of the cord it 110 crosses and then underneath the next succeeding cord crossed by it. At each operation the crossed portions are driven down by the comb compacting the mesh, the formation of which is the same as square woven 115 fabric except that the cords extend at substantially an angle of 45° to the longitudinal dimensions of the fabric.

Within the tube 5 mechanism is provided 120 for feeding the fabric downward and mechanism for holding the fabric from moving up or down, (see Fig. 3). The feeding mechanism is composed of a segmental expanding ring 68, (the outer surface of which is provided with teeth to engage the fabric and 125 insure a positive movement thereof with the plate during the feeding operation), and arms or levers 69 fulcrumed on a ring 69' fixed on the lower end of the tubular shaft 70 so that the ring 68 moves with such shaft 130

70. The said holding mechanism is composed of an expanding segmental ring 71, corresponding to the ring 68, and levers 72 fulcrumed on inwardly projecting lugs on 5 the casting or part 73. This casting or stationary part 73 is attached to the stationary vertical shaft 74, which is in turn supported by bracket 75 on the main frame 3. The levers 69 and 72 are operated by the 10 ring cams 76 and 77, respectively, which engage the flattened portions of the free ends of the levers and cause these free ends of the levers to move outward, thereby pulling inward the ends of the levers attached to the 15 respective rings 68 and 71 contracting such rings to disengage the fabric. These ring cams 76 and 77 are mounted on the tubular shaft or sleeve 78 and are so spaced apart that the respective levers 69 and 72 are not 20 actuated simultaneously but are operated alternately as the sleeve 78 is reciprocated. The tubular shaft or sleeve 70 is provided with a plurality of vertical slots. Through these slots lugs on the ring 76 extend to and 25 are attached to the sleeve 78 (see Fig. 26). The sleeve 78 is reciprocated by means of the cam 79, (Figs. 2 and 24), levers 80 and 81, connecting rod 82, levers 83 and 84, (Figs. 1 and 24), connecting rod 85, lever 30 86 and collar 87, attached to the sleeve 78.

The rings 68 and 71 are automatically expanded by compression springs 72' which press inwardly on the flattened ends of levers 69 and 72 and cause the ends attached 35 to rings to press outward on the rings causing them to engage the fabric.

The sleeve 70 is actuated by means of the adjustable screw 88 (Figs. 1 and 24) on the lever 85 coming into contact with the end 40 portion of the lever 89 pushing it down to the predetermined distance in accordance with the adjustment of the screw 88. The lever 89 pushes down on the collar 90 (Fig. 2) attached to the sleeve 70, thereby causing 45 the downward movement of the sleeve 70 and feeding element composed of the ring 68 and levers 69. The return movement of the lever 89 upward is caused by the spring 91 attached to the lever 89 and to a lug on 50 the bracket casting 75 of the main frame 3.

The adjusting screw 88 on the lever 85 is so set that it just makes contact with the end of the lever 89 when the comb 60 has driven the crosses in the cords up to or near 55 the edge of the tube 5 and into the required compactness. Upon the continued downward movement of the comb the sleeve 70 and feeding element (composed of ring 68 and levers 69) are carried downward causing 60 the fabric in the tube 5 to be moved down permitting the newly formed meshes to pass over the edge of and into the tube 5. Just prior to the downward movement of this feeding element the cam 79 will have 65 caused the ring cam 77 to move down push-

ing the ends of the levers 72 outward and contracting the ring 71, thereby releasing it from the fabric and permitting the ring 68 (which is expanded) to carry the fabric down. After the fabric has been thus 70 moved downward the cam 79 pulling the sleeve 78 upward causes the ring cam 77 to pass out from the ends of the levers 72 and the ring cam 76 to move under the ends and push outward on the levers 69. This expands the ring 71 which holds the fabric from further movement in either direction and contracts the ring 68 releasing the same from the fabric. At this time the comb starts upon its upward movement and simultaneously the upward movement of the screw 88 permits the spring 91 to pull upward on the lever 89, thereby raising the feed element to its upper position. Following this upward movement of the feed element, the cam 79 again pushes down on the two ring cams 76 and 77 causing the segmental ring 68 to expand and engage the fabric and the segmental ring 71 to contract and release the fabric. The feed mechanism 80 is then ready for another operation.

The fabric after passing down through the tube 5 passes under a bar 92 (Fig. 2) which flattens it out preparatory to winding in a roll. The fabric then passes to a roller 93, (Figs. 15 and 16), suspended on two oscillating arms 94 which are under constant tension of springs 95. From this roller 93 the fabric passes over and is wound upon the roll 96 which takes up the fabric at a 100 constant speed. As the fabric is fed down the tube 5 intermittently the arms 94 and roller 93 oscillate back and forth maintaining a constant tension on the fabric. The winding roller 96 is supported and driven by 105 two short shafts mounted in the bearings 97. The driving gear 99 is driven by the worm 100 on the cam shaft 101. The gear 99 drives the shaft 98 by the usual well known frictional means common in textile machinery and 102 represents the means for adjusting the pressure on the leather friction disks thereof.

Fig. 17 shows a form of slipping chuck 103 such as is common in textile machinery 115 wind-up mechanism.

In the drawings I have illustrated each of the shuttle tubes 18 as carrying two spools. It is obvious that, if desired, each tube 18 may handle two cords or threads and the 120 fabric be formed with double threads.

Using Fig. 6 as a diagram of the movements of the shuttle tubes 18, assume that at A the circles a, b, c, d, e, f represent the two full sets of shuttle tubes 18 all in the upper 125 position in plate 25 and forming a complete circle around the machine. a, c and e are one set or series and are oscillated to the left and b, d and f are the other set oscillated to the right, as indicated by the arrows through 130

them. B indicates the position of the tubes just after the lower frame has carried *b*, *d*, *f* to lower position. After this operation the oscillation of the upper and lower frames 5 takes place in the direction of the horizontal dotted arrows and each oscillates the distance of one space or track, thus carrying series *a*, *c*, *e* to the left to the position formerly occupied by *f*, *b*, *d*, respectively, which were 10 carried to the right. Upon all of the tubes returning to the upper position they will then assume the respective positions shown at C, viz:—*f*, *c*, *b*, *e*, *d*, *a*. D indicates the next oscillation and in this case *c*, *e*, *a* are 15 carried to the lower position and as indicated by the arrows the oscillation is in the reverse direction of the preceding oscillation, thus carrying *f*, *b*, *d* to the right and *c*, *e*, *a* to the left one space. E indicates the 20 arrangement of the tubes after again returning to the upper position (all in the plate 25), such order then being *c*, *f*, *e*, *b*, *a*, *d*.

It will be noted that through all of the 25 operations *a*, *c*, *e* have been advancing to the left while *b*, *d*, *f* have been moving to the right and the relative position of each tube in each set has not been changed. In other words, each set of tubes has moved in its 30 respective direction alternately over and under without changing the relative position of its respective tubes to one another.

The foregoing description is of the preferred form of machine embodying my invention as applicable to the producing of tubular bias fabric. In such case the plates 25, 26 and hooks 17 extend entirely around the machine and one series of shuttle tubes 18 continuously advances around in one direction and the other series of shuttle tubes 40 around in the other direction. In the drawings, however, I have also illustrated my invention as embodied in such form of machine as to produce flat bias fabric with selvage 45 edges. When utilized for this purpose it is necessary that the direction of movement or advancement of the respective series of tubes about the machine be reversed when the tubes of the respective series reach the point 50 corresponding to the edge of the fabric. This reversing mechanism is illustrated in Figs. 4 and 5 of the drawings. (Reference may also be had to Fig. 21, in which however the segmental frame 35 is shown in two 55 parts and adapted for the reversal of a plurality of the shuttle tubes at a single operation when a plurality of tubes of each set or series are actuated in pairs or in multiple to weave fabric having double or plural parallel threads instead of the mesh being formed of single cords or threads.)

To accommodate this reversing mechanism a segmental aperture is made in the upper frame 1 and in this aperture is mounted a 65 segmental circumferentially movable shut-

tle-tube supporting frame 35, very similar in cross section to the frame 1. 35', 35' represent two curved bars, the ends of which are mounted on portions of the frame 1 adjacent the aperture and fixed in position by 70 suitable screws. The frame 35 is provided with bosses 35^a (Fig. 5) in which segmental channels are formed adapted to receive the bars 35' upon which the frame 35 moves. Top plates 35^b are secured on the top of the 75 bosses 35^a and extend the width of the frame 35. It is thus seen that although the frame 35 moves with the frame 1 in its oscillation, such frame 35 may also be oscillated on the bars or tracks 35' the width of the aperture 80 in the frame 1.

In connection with this segmental reversing plate on frame 35 and for mutual co-operation therewith certain other changes, modifications or additions have been made. 85 Assuming for the purpose of this description, that we are at the side of the machine and facing the reverse mechanism on the machine: The oscillation (to the right or to the left), of either the frame 1 or of the 90 frame 2 is only equal to the distance from one slot or track in the plate 25 or 26 to another. Assuming that the upper frame has been oscillated to the left, (Fig. 5) the pair of hooks of the lower frame, which will then 95 register with the pair of hooks in the slots of the upper frame adjacent to the right hand edge of the aperture in the upper frame have been replaced by hooks 39, as have also the pair of hooks next adjacent 100 thereto at the left. Again assuming that the upper frame has been oscillated to the right, the pair of hooks of the lower frame which then register with the pair of hooks in the slots of the upper frame adjacent the 105 left hand edge of said aperture have been replaced by hooks 39, as have also the pair of hooks next adjacent thereto at the right. In connection with each of the slots 46 and 47 of the plate 35 is provided a pair of hooks 110 36. Each pair is preferably connected by a rod and with a spring adapted to normally hold the hooks in operative position.

The frame 35 is mounted and positioned so that the shuttle-tube hooks 36, mounted 115 upon it, will register with the hooks 39 of the lower frame part 6. This segmental frame 35 is oscillated in the frame 1, its amount of movement corresponding to the oscillation of the frame 1. This oscillation 120 of this frame 35 is entirely independent of its oscillation with the frame 1 and is imparted to it by a lever 37 connected to the hook-operating ring 19 so that at each movement of the ring 19 the segmental frame 35 125 is moved from one side to the other of the aperture in the frame 1. The frame 35 carries a segmental guide or track plate 38, substantially corresponding to the guide or track plate 25 on the upper frame 1, and 130

provided with a slot near each side so spaced that each of the slots will register with a slot in the lower guide or track plate 26 when the plate 35 is oscillated to either side of the 5 aperture in the frame 1. The hooks 36 of the frame 35 are under constant spring tension tending to automatically hold them in hooked-up position. The opposing hooks 39 carried by the lower frame parts 6 and 7, respectively, are mechanically operated by the cam 40 (Figs. 1 and 19), levers 41 and 42, rocker arm 43 and connecting rods 44, 45, (Figs. 1 and 5). As shown in Fig. 5 the rod 10 44 is composed of two parts slidably connected to each other, as shown at 44'. Each of these parts has an eye or loop at its end through which the other part operates. A sleeve is preferably mounted upon one of these and between the two eyes. This sleeve 15 serves to insure guiding the movement of the parts with respect to each other and prevent bending. When the lower frame moves downward the parts of this rod 44 are moved relative to each other to prevent bending of 20 the rod. Another purpose of this construction is to provide for the operation of the hooks 39 of the lower frame when in position directly beneath the mechanically operated hooks 17 of the upper frame 1 and the 25 lower frame is raised to bring these hooks 39 and these hooks 17 into operation for the transference of the shuttle-tubes from one set of said hooks to the other. In such operation the hooks 39 act as spring-actuated hooks only and are operated by such 30 mechanically operated hooks 17 of the upper frame. As shown in Fig. 5 a spring 39' is provided to automatically normally hold the hooks 39 in hooked-up position.

40 Assuming that the upper frame has oscillated to the right and the lower frame to the left and that all of the shuttle tubes are in the upper position, and assuming we are facing the machine and reverse mechanism, 45 the frame 35 will be standing to the right side of the aperture in the main frame. Upon the succeeding downward movement of the lower frame the hooks 39 will engage the tube *n* (Fig. 4) carrying it to the lower 50 position, (tube *n* being one of the set or series of tubes moving to the right. The entire set or series are carried to the lower position by this same downward movement of the frame 2). The lower frame then 55 oscillates to the right carrying the tube *n* to the right, the upper frame simultaneously oscillating to the left, carrying with it the frame 35 and its reversing slot 46. This brings the tube *n* directly under slot 46 of 60 frame 35. The lower frame then raises putting the tube *n* in slot 46 of the frame 35. The action of the cam 40 then causes the hooks 39 to be disengaged and the hooks 36 on segment 35 to engage the tube *n*. The 65 movement of the hook-operating ring 19 to the left actuates the arm 37 into contact with the projection 37' on the plate 35^b oscillating the plate 35 to the left side of the aperture in the main frame. This action carries the tube *n* to a position directly over 70 a slot in the lower guide plate 26, which is the position of a tube of the set or series moving to the left. The next operation of the cam 40 then takes place, causing the hooks 39 to engage the tube *n* and disengage 75 the hooks 36. The lower frame then carries the tube *n* downward and then oscillates to the left. The tube *n* has now become one of the set or series of tubes moving to the left. It is thus seen that the tube *n* is carried from 80 the upper frame to the lower frame and then the next oscillation of the lower frame to the right carries this tube *n* into position for the next movement of the lower frame upward to deliver it into the slot 46 of the 85 reversing plate 35. The lower frame then moves upward and the tube *n* is taken from the pair of hooks 39 of the lower frame by the pair of hooks 36 of the reversing plate 35. The plate 35 then moves laterally to the 90 left in the upper frame during the time the upper and lower frames are at rest. The hooks 39 are then actuated to release the tube *n* from the hooks 36, and to engage and carry the tube *n* on the lower frame. The 95 lower frame then moves down carrying the tube *n* down with it. The tube *n* has now become one of the series of tubes moving to the left. When the frame 35 moved to the left in the aperture of the main frame in 100 thus reversing the tube *n*, this movement brought the frame 35 in position to receive the tube *o* into the slot 47. The oscillation of the lower frame to the left (just referred to and which carried the tube *n* to the left) 105 carried the tube *o* to a position directly under the slot 47. The tube *o* was one of the series of tubes moving to the left and was taken out of the last slot in the upper frame (the slot adjacent to the edge of the aperture at our right as we look toward the machine and into the reverse mechanism) by the downward movement of the lower frame just prior to the oscillation to the left just referred to. The next upward movement of 110 the lower frame brings the tube *o* into slot 47 of the segmental frame 35 and, after the hooks 39 have been disengaged by the action of the cam 40, etc., and the hooks 36 have engaged such tube, the frame 35 is actuated 115 to the right carrying tube *o* to position directly over a slot in the lower guide plate 26 which is the position for the next tube of the set moving to the right. It is thus seen that as a tube of a given set reaches the slot 120 adjacent the aperture in the main frame it is taken up by the segmental frame 35 and moved to a position to become a member of the set or series moving in the other direction. 125

130

Referring to Fig. 7 the action of this reverse mechanism may be diagrammatically illustrated. F indicates the shuttle tubes all in the upper position with *g*, *h*, *i*, *j*, *k*, *l*, *m* as the relative positions of the tubes. *g*, *i*, *k*, *m* are the set moving to the right and *h*, *j*, *l* are the set moving to the left. G shows the position after *g*, *i*, *k* and *m* have moved to the lower position and just prior to the oscillation which will carry *g*, *i*, *k*, *m* to the right and *h*, *j*, *l* to the left. After this oscillation takes place and *m* has reached the end of travel or progression to the right and the tubes have reached the upper position, 15 the reverse mechanism gives the tube *m* a reverse oscillation of one space, putting it in the position of a tube of the set or series moving to the left and the tube *m* thereafter becomes one of that set and travels in 20 that direction until again reversed when it reaches the end of travel or progression to the left. H illustrates the position of the tubes after they have reached the upper position and after the reversal of tube *m*. The 25 illustration of diagram I is substantially the same as that of G except the oscillation is reversed and the reverse mechanism on the left is operating with tube *h* as indicated by the arrows and *h* becomes one of the set of 30 tubes moving to the right. J illustrates the relative positions of the tubes in upper position after I operation. K is substantially the same as G except that *k* tube is being reversed to become one of the set traveling 35 to the left. L shows the relative positions of the tubes in the upper position after K operation. It will be noted that reversal takes place alternately at one end and another according to the direction of oscillation.

40 The foregoing description of such reverse mechanism applies to the machine when used to form single cord flat bias fabric or when each shuttle tube 18 is provided with two spools and handles two cords or threads, 45 thus making the mesh with two parallel sets of threads.

When the machine is to be operated to produce fabric having a multiple of parallel cords or threads forming the mesh as indicated in Figs. 13 and 14, instead of alternate shuttle tubes 18 (in upper position) belonging to the respective series moving to the right or left, such alternation is of sets or groups, viz., if two cord fabric is to be produced the set or group is of two tubes 18 and if three or four cord fabric is to be produced, such alternation is of sets or groups of three or four tubes 18, respectively. Taking a four cord fabric as an illustration 60 and assuming all the tubes 18 are in upper position the first four would be of the series moving to the right, the next four of the series moving to the left, and so on through the number of tubes. Each vertical oscillation

of the lower frame would handle these 65 tubes in groups or sets of four. Otherwise the operation corresponds to the actuation of single tubes. The amount of oscillation of the frames 1 and 2 respectively must be adjusted so as to correspond to the distance between the number of tubes so handled as a group or set. With a group of four the amount of oscillation would equal four slots in the plate 26. This adjustment is secured by changing the position of the connecting rod 29 on the lever 28 and on the lever 30. In Fig. 24 this adjustment is shown for handling the tubes 18 in groups or sets of three. If the groups were of two tubes each the connecting rod 29 would be 80 connected at the center of the lever 28. If the multiple group is of four tubes 18 each the connection rod 29 would be connected with the plate 28 at the center thereof and its connection with the arm 30 would be at 85 the center thereof.

In Fig. 21 I have illustrated the reverse mechanism as applicable to use when the sets or series of tube carriers are in alternated multiples of four. With such a construction instead of every alternate tube carrier belonging to a given series, four successive tube carriers would belong to one set of tube carriers oscillating in one direction, the next four to the set oscillating in 95 the other direction, and so on alternately through the entire number of tube carriers. With this arrangement it would be of course necessary to reverse four tube carriers at a time. Instead therefore of the segmental 100 frame 35 being provided with one slot 46 at its left side and one slot 47 at its right, it would be provided with a set of four slots 46 and 47 respectively at its sides, as indicated in Fig. 21. The segment cut from the 105 frame 1 would be proportionately larger. In Fig. 21 the frame 35 is shown as made in two pieces. It is obvious that it may be in either one or two pieces as preferred, for when in two pieces the two parts act as one 110 plate, being fixed together by the top plates 35^b. When using the tubes in groups or multiples of four it will also be necessary to change eight of the pairs of suitably positioned hooks 17 of the lower frame instead 115 of two as heretofore described in connection with the reverse mechanism as applied to reversing a single tool. The frame 35 will be provided with a pair of hooks 36 for each slot 46, 47. Otherwise the mode of operation and action of the reversing mechanism are substantially the same.

In Fig. 11 I have shown a section of flat bias fabric and illustrated the manner in which longitudinal cords 110 may be inserted in the selvage or in any part of the mesh of the fabric. This is accomplished by means of spool holding and thread guiding

bracket and support shown at M in Fig. 3. This bracket M comprises a spool 103', supporting arms 104, tension spring 105, guide tube 106, clamp 107, by which this mechanism is fixed on the supporting ring 109 of the frame. 108 represents a drag spring which bears on the body of cord on the spool 103' frictionally resisting the unwinding thereof. The supporting ring 109 extends 5 entirely around the machine and the desired number of brackets M may be positioned at any point as desired. By this means a cord 110 may be fed radially toward the edge of the tube 5 and inasmuch as the holding and 10 feeding device of this cord 110 does not oscillate or move with either the upper or lower frame 1 or 2 of the machine the shuttle tubes 18 form the fabric around this cord as they are carried over and under this 15 cord by means of the oscillations of the frames 1 and 2. It is obvious therefore that this cord 110 at no time moves out of radial position with respect to the tube 5 except as it is slightly pushed up vertically 20 by the lower frame 2 when the latter is in its upper position, as indicated in dotted lines in Fig. 3. From this position, however, it is immediately pulled down by the tension of the spring 105 when the lower frame 2 25 reciprocates downwardly. The cord 110 is unwound from spool 103' as the feed of fabric takes place. The drag spring 108 prevents the spool from spinning or unwinding any more cord than just sufficient 30 to correspond with the feed of the fabric. The tension spring 105 maintains a uniform tension on the cord and takes up any slack in the same. The guide tube 106 locates the exact position of the cord 110 as it enters 35 between the edges of the guide plates 25 and 26 and is fed into the fabric at the edge of the tube 5. Referring again to Fig. 7, it will be understood that as the reverse mechanism reverses each shuttle tube and places 40 it in the position of the set of tubes traveling in the opposite direction, such tube is carried entirely around the longitudinal cord 110 placed in the selvage. It is obvious that the fabric may be formed with or without 45 the insertion of the longitudinal cords. The object of placing such longitudinal cords in the fabric is in order to prevent longitudinal stretching of the fabric when, for instance, the fabric is to be used in the manufacture of the carcass of pneumatic tires 50 during the calendering process of the fabric. After the rubber has been calendered into the fabric in such process the longitudinal cords may be trimmed out, permitting the 55 fabric to stretch as required to conform to the shape of the tire core.

A motor 111 is provided with a shaft 112 on which is mounted a pinion 113 which drives the gear 114. The shaft 115 of gear

114 is provided with a pinion 116 which 65 meshes with a gear 117 mounted on the shaft 101. Cams 27, 40 and 48 are mounted on the shaft 118 and rotate therewith. The shaft 115 is also provided with a pinion 119 which meshes with a gear 120, said gear 70 120 being keyed to a hollow shaft 121. The cams 61, 10 and 79 are mounted on said hollow shaft 121 and rotate with it, the location of the said cams on their shafts being fully shown in Fig. 25 and the curvature of 75 their tracks and their relative arrangement illustrated in Figs. 18 and 19.

It is obvious that various modifications may be made in the construction of machine 80 illustrated in the drawings and described and that various mechanical equivalents may be substituted for the various elements, parts and mechanisms within the purview of my invention.

I claim:

1. A bias fabric machine comprising two frames, means for simultaneously oscillating said frames in opposite directions, means for moving one of said frames toward the other between each oscillation, a series 90 of thread-carriers mounted on each frame, and means for changing the respective series of carriers from one frame to the other frame upon the movement of one of said frames toward the other. 95

2. A bias fabric machine, comprising two frames, means for simultaneously oscillating said frames in opposite directions, means for moving one of said frames toward the other between each oscillation, a series 100 of thread-carriers mounted on each frame, means for changing the respective series of carriers from one frame to the other frame upon the movement of one of said frames toward the other, and reversing mechanism 105 for transferring carriers of one series to the other series when such carriers have reached predetermined positions.

3. A bias fabric machine comprising two frames, means for simultaneously oscillating said frames in opposite directions, means for moving one of said frames toward the other between each oscillation, a series 110 of thread-carriers mounted on each frame, means for transferring the respective series of carriers from one frame to the other upon the movement of one of said frames toward the other, and means for compacting the fabric thread after it has 115 been formed.

4. A bias fabric machine comprising two frames, means for simultaneously oscillating said frames in opposite directions, means for moving one of said frames toward the other between each oscillation, a series 120 of thread carriers mounted on each frame, means for transferring the respective series of carriers from one frame to the other upon 125

- the movement of one of said frames toward the other, tension means for holding the fabric as formed, and means for compacting the fabric mesh after it has been formed.
5. A bias fabric machine comprising two frames, means for simultaneously oscillating said frames in opposite directions, means for moving one of said frames toward the other between each oscillation, a series 10 of thread carriers mounted on each frame, means for transferring the respective series of carriers from one frame to the other upon the movement of one of said frames toward the other, reversing mechanism for transferring 15 carriers of one series to the other series when such carriers reach predetermined positions, tension means for holding the fabric as formed, and means for compacting the fabric mesh after it has been formed.
10. A bias fabric machine having a plurality of series of thread carriers, thread-carrier operating mechanism for moving said respective series progressively in opposite directions simultaneously and through 20 each other, said progressive movements alternating with said movements through each other, and reversing mechanism for transferring carriers of one of said series to the other series when such carriers have 25 reached predetermined positions.
7. A bias fabric machine having thread carriers, thread-carrier supporting and operating mechanism for separating said carriers into two series and for moving said 30 respective series progressively in opposite directions simultaneously and through each other, said progressive movements alternating with said movements through each other, and reversing mechanism for transferring carriers of one of said series to the other series when such carriers have 35 reached predetermined positions.
8. A bias fabric machine having a plurality of series of thread carriers, thread-carrier supporting and operating mechanism for moving said respective series progressively in opposite directions simultaneously and through each other, said progressive movements alternating with said movements 40 through each other, reversing mechanism for transferring carriers of one series to the other when such carriers have reached predetermined positions, means for holding under tension the interwoven threads, and 45 means for compacting the meshes.
9. In a bias fabric machine, a thread-carrier supporting frame having an oscillating movement about a central axis and a reciprocating movement longitudinally 50 of said axis.
10. A bias fabric machine having a plurality of series of thread carriers, thread-carrier supporting and operating mechanism for moving said respective series progres-

sively in opposite directions simultaneously and through each other, said progressive movement alternating with said movements through each other, reversing mechanism for transferring carriers of one series to the other when such carriers have reached predetermined positions, means for holding under tension the interwoven threads, means for compacting the meshes, and means for taking up or feeding along the compacted fabric.

11. In a bias fabric machine, a tubular fabric guide, means for compacting the meshes adjacent the end of said guide, and means for feeding into and retaining within said guide the completed fabric.

12. A bias fabric machine having frames, oscillating with respect to each other, two series of thread-carriers alternately carried by said respective frames and transferred from one frame to the other after each oscillation, and reversing mechanism for transferring carriers of one series to the other when such carriers have reached predetermined positions.

13. In a bias fabric machine, a tubular fabric guide and feeding mechanism within said guide.

14. A bias fabric machine having frames oscillating with respect to each other, devices on said frames for engaging and carrying thread carriers, a series of thread carriers for each of said respective frames, means for transferring said respective series of thread carriers from one frame to the other frame after each oscillation, and reversing mechanism for transferring carriers of one series to the other when such carriers have reached predetermined positions.

15. A bias fabric weaving machine having frames, means for oscillating said frames with respect to each other, mechanism for moving one of said frames toward the other after each oscillation, devices on said frames for engaging and carrying thread-carriers, and a series of thread-carriers for each of said respective frames, said thread-carriers carrying devices actuated to transfer said respective series of thread-carriers from one frame to the other after each oscillation.

16. A bias fabric weaving machine having frames, means for oscillating said frames with respect to each other, mechanism for moving one of said frames toward the other after each oscillation, devices on said frames for engaging and carrying thread-carriers, a series of thread-carriers for each of said respective frames, said thread-carrying devices actuated to transfer said respective series of thread-carriers from one frame to the other after each oscillation, and reversing mechanism for transferring carriers of one series to the other series when such

carriers have reached predetermined positions.

17. A bias fabric weaving machine having frames, means for oscillating said frames with respect to each other, mechanism for moving one of said frames toward the other after each oscillation, devices on said frames for engaging and carrying thread-carriers, a series of thread-carriers for each of said respective frames, said thread-carrying devices actuated to transfer said respective series of thread-carriers from one frame to the other after each oscillation, reversing mechanism for transferring carriers of one series to the other series when such carriers have reached predetermined positions, means for holding the mesh produced by said thread carriers, and means for compacting the meshes.

10 18. A bias fabric machine having two annular thread-carrier supporting and actuating frames, means for oscillating said frames in opposite directions about a common axis, a series of thread-carriers arranged in spaced relation on each of said frames, and means for reciprocating one of said frames longitudinally of said axis and simultaneously exchanging the respective series of thread-carriers from their respective frames to the other frame.

25 19. A bias fabric machine having two annular thread-carrier supporting and actuating frames, means for oscillating said frames in opposite directions about a common axis, a series of thread-carriers arranged on each frame, means for reciprocating one of said frames longitudinally of said axis and simultaneously exchanging the respective series of thread-carriers from their respective frames to the other frame, and reversing mechanism for transferring carriers of one series to the other series when such carriers reach predetermined positions.

20 20. A bias fabric machine having means for holding the fabric under tension as it is woven, two frames mounted to oscillate in opposite directions about said means, means for moving one of said frames toward and away from the other between each oscillation of said frames, a series of thread carriers for each of said respective frames, and means for transferring said respective series of thread carriers from one frame to the other upon each actuation of one of said frames toward the other.

25 21. A bias fabric machine having means for holding the fabric under tension as it is woven, two frames mounted to oscillate in opposite directions about said means, means for moving one of said frames toward and away from the other between each oscillation of said frames, thread-carrier supporting and exchanging mechanism carried by said frames, a series of thread carriers on each

of said frames, the said carriers being arranged in spaced relation to each other so that the carriers on one frame at the end of an oscillation of the frames register with the vacant thread carrier and exchanging means on the other frame.

26 22. A bias fabric machine having means for holding the fabric under tension as it is woven, two frames mounted to oscillate in opposite directions about said means, means for moving one of said frames toward and away from the other frame between each oscillation of said frames, means on each of said frames for supporting thread carriers thereon and exchanging the same between the respective frames upon the movement of one of said frames toward the other, and a series of thread carriers carried by each of said frames and maintained in radial position with respect to said first named means.

27 23. A bias fabric machine having mechanism for holding the fabric as it is woven, a plurality of series of thread carriers, and means for maintaining each of said carriers in radial position with respect to said mechanism and for moving the respective series progressively in opposite directions about said mechanism and through each other, said progressive movements alternating with said movements through each other.

28 24. A bias fabric machine having mechanism for holding the fabric as it is woven, a plurality of series of thread carriers, two frames mounted to oscillate in opposite directions about said mechanism, means for moving one of said frames toward and away from the other frame between each oscillation, and mechanism in connection with each frame for supporting and maintaining on the respective frames each of said carriers in a radial position with respect to said first named mechanism during the movements of said frames and for exchanging the carriers from one frame to the other at each movement of one frame toward and away from the other.

29 25. A bias fabric machine having mechanism for holding the fabric as it is formed and having two frames oscillating simultaneously in opposite directions about the same axis, two series of thread carriers, each series alternately carried by respective frames and transferred to the other frame between each oscillation, and means for maintaining each of said carriers in radial position with respect to said fabric holding mechanism.

30 26. A bias fabric machine having mechanism for holding the fabric as it is formed, two frames, mechanism for oscillating said frames simultaneously in opposite directions about the same axis, two series of thread carriers, said respective series of thread car-

riers alternately actuated by said respective frames, means for maintaining each of said carriers in radial position with respect to said fabric holding mechanism, and reversing mechanism for transferring carriers of one series to the other series when such carriers reach predetermined positions.

27. A bias fabric machine having two frames, mechanism for oscillating said frames simultaneously in opposite directions about the same axis and toward and away from one another between each oscillation, two series of thread carriers, thread-carrier supporting and exchanging mechanism carried in spaced relations on said frames, mechanism for actuating said last named mechanism to exchange the thread carriers from one frame to the other upon each actuation of the frames toward and away from each other, and reversing mechanism for transferring carriers of one series to the other series when such carriers have reached predetermined positions.

28. In a bias fabric machine, a thread-carrier and means for delivering a plurality of threads to said carrier, said carrier provided with means for concentrating the threads in close parallel relation.

29. In a bias fabric machine, a plurality of thread-carriers, means for delivering a plurality of threads to each of said carriers, said carriers provided with means for delivering the threads in close parallel relation, and mechanism for moving said carriers in two spaced series in opposite directions transversely about a central axis and for moving said series through each other, said transverse movement alternating with the movements of said series through each other.

30. A bias fabric machine having two frames, mechanism for simultaneously oscillating said frames in opposite directions about a hollow shaft and a movement toward and away from each other between oscillations, two series of thread carriers arranged to furnish threads to the interior of said shaft, means for holding said threads in position in said shaft, and means for supporting each series of thread carriers on one of said frames during oscillation and for exchanging the series from one frame to the other at each operation of the frames toward and away from each other.

31. A bias fabric machine having two frames, mechanism for simultaneously oscillating said frames in opposite directions about a hollow shaft and a movement toward and away from each other between oscillations, two series of thread carriers arranged to furnish threads to the interior of said shaft, means for holding said threads in position in said shaft, and means for supporting each series of thread carriers on one

of said frames during oscillation and for exchanging the series from one frame to the other at each operation of the frames toward and away from each other, and for transferring carriers of one series to the other series when such carriers have reached predetermined positions.

32. A bias fabric machine comprising two annular frames, a tubular shaft, means for reciprocating said frames in opposite directions about said shaft as an axis, a series of thread-carriers operatively mounted on each frame, means for moving each series from one frame to the other after each oscillation, and means for feeding the fabric into said tubular shaft.

33. A bias fabric machine comprising two frames, a tubular guide or shaft, means for reciprocating said frames in opposite directions about said shaft as an axis, a series of thread-carriers operatively mounted on each frame, means for moving each series from one frame to the other after each oscillation, reversing mechanism for transferring carriers of one of said series to the other when such carriers reach predetermined positions, and means for feeding the fabric into said tubular guide.

34. A bias fabric machine comprising two frames, means for reciprocating said frames in opposite directions about an axis, a series of thread-carriers for each frame, means for supporting and maintaining said carriers on their respective frames in radial position with respect to said axis, and means for transferring each series from one frame to the other after each oscillation.

35. A bias fabric machine having mechanism for holding the fabric as formed, two series of thread-carriers, means for maintaining each of said carriers in radial position with respect to said mechanism, and means for actuating said series of thread-carriers progressively in opposite directions about said mechanism and through each other, said progressive movements alternating with said movements through each other, and means for inserting a longitudinal thread at a line of intersection of interlaced threads to prevent longitudinal stretch of the fabric.

36. A bias fabric machine having means for producing bias fabric, a tubular guide to receive the same, means adjacent the edge of said guide for compacting the meshes, means for holding said fabric under tension while produced and compacted, and means for feeding said fabric into said guide.

37. A bias fabric machine having means for producing bias fabric, a tubular guide to receive the same, a comb for compacting the meshes thereof, means for actuating said comb, and means in operative connection with said guide for holding the fabric dur-

ing the operation of said comb and for feeding the fabric into said guide.

38. In a bias fabric machine, a mesh compacting mechanism having a plurality of 5 wedge shaped blades, and means for actuating said mechanism.

39. In a bias fabric machine, two frames each provided with an annular slotted plate, means for oscillating said frames simultaneously in opposite directions, each of said frames having a series of thread-carriers positioned in alternate slots of its plate, and means on each frame for supporting the carriers during the oscillation of said frames 10 and for transferring the carriers from one frame to the other between each oscillation of the frames.

40. In a bias fabric machine, two frames each provided with an annular slotted plate, 20 means for oscillating said frames simultaneously in opposite directions, each of said frames having a series of thread-carriers positioned in alternate slots in its plate, each frame having a pair of supporting hooks in 25 connection with each of the slots of its plate, and means for actuating the hooks of one frame between each oscillation of the frames to transfer the carriers of one frame to the other.

30 41. In a bias fabric machine, two frames each provided with an annular slotted plate, means for oscillating said frames simultaneously in opposite directions, means for moving one of said frames toward the other between oscillations of said frames, each of 35 said frames having a pair of supporting hooks in connection with each of the slots in its plate, a series of thread-carriers positioned in alternate slots in each plate, and 40 means for actuating the hooks upon the movement of the one frame toward the other to transfer the carriers from each frame to the other.

42. In a bias fabric machine, two frames 45 each provided with an annular slotted plate, one of said plates being segmental, means for oscillating said frames simultaneously in opposite directions, each of said frames having a series of thread-carriers positioned 50 in alternate slots of its plate, means on each frame for supporting the carriers during the oscillation of the frames and for transferring the carriers from each frame to the other between each oscillation of the frames, 55 and reversing mechanism for transferring carriers of one series to the other when such carriers reach predetermined positions.

43. In a bias fabric machine, two frames each provided with an annular slotted plate, 60 one of said plates being segmental, means for oscillating said frames simultaneously in opposite directions, each of said frames having a series of thread-carriers positioned in alternate slots of its plate, means on each

frame for supporting the carriers during 65 the oscillation of the frames and for transferring the carriers from each frame to the other between each oscillation of the frames, a slotted reversing plate mounted in the segmental opening of said segmental plate, said 70 reversing plate oscillating in unison with said segmental plate and provided with carrier supporting means in connection with its slots, mechanism for actuating said last named carrier supporting means between 75 each oscillation of the frames to transfer carriers to or from said reversing plate from or to the opposite frame, and means for oscillating said reversing plate between each oscillation of said frames. 80

44. In a bias fabric machine, two frames each provided with an annular slotted plate, one of said plates being segmental, means for oscillating said frames simultaneously in opposite directions, means for moving one 85 of said frames toward the other between the oscillations of the frames, each of said frames having a series of thread-carriers positioned in alternate slots of its plate, means on each frame for supporting the carriers during the oscillation of the frames and for transferring the carriers from each frame to the other between each oscillation of the frames, a slotted reversing plate mounted in the segmental opening of the 90 segmental plate, said reversing plate oscillating in unison with said segmental plate and provided with carrier supporting means in connection with its slots, mechanism for actuating said last named carrier supporting means between each oscillation of the frame to transfer carriers to or from said reversing plate from or to the opposite frame, and means for oscillating said reversing plate between each oscillation of 95 said frame. 100

45. A bias fabric machine having thread carriers each constructed to carry and deliver a plurality of threads and means for simultaneously moving said carriers in two 110 series in opposite directions and back and forth between one another.

46. A bias fabric machine having frames, means for oscillating said frames with respect to each other, and two series of thread-carriers alternately carried by said respective frames and transferred from one frame to the other after each oscillation, each thread-carrier constructed to carry and deliver a plurality of threads. 115

47. A bias fabric machine having two frames, means for oscillating said frames simultaneously in opposite directions about the same axis, and two series of thread-carriers, each series alternately actuated by each of said respective frames, each thread-carrier constructed and arranged to carry and deliver a plurality of threads. 120 125

48. A bias fabric machine having two frames, means for oscillating said frames simultaneously in opposite directions about the same axis, and two series of thread-carriers, each series alternately actuated by each of said respective frames, each thread-carrier constructed and arranged to carry and deliver a plurality of threads in close parallel relation.
- 10 49. A bias fabric machine having thread carriers each comprising a tubular body portion through which a thread passes, a spool supporting frame, and a thread guide tip.
- 15 50. A bias fabric machine having thread carriers each comprising a tubular body portion through which a plurality of threads pass, a plurality of spools mounted on each body, and a thread guide tip constructed to deliver the threads in flat parallel formation.
- 20 51. A bias fabric machine having thread carriers comprising a tubular body portion through which a thread passes, a spool supporting portion, and a guide tip portion.
- 25 52. A bias fabric machine having means for oscillating two series of thread-carriers simultaneously in opposite directions and for passing the respective carriers of one series through between the carriers of the other series after each oscillation, said thread carriers each comprising a tubular body portion through which a thread passes, a spool supporting portion, and a guide tip portion.
- 30 53. A bias fabric machine having means for oscillating two series of thread-carriers simultaneously in opposite directions and for passing the respective carriers of one series through between the carriers of the other series after each oscillation, said thread carriers each comprising means for supporting a plurality of thread supplies, and means for delivering a plurality of threads in close flat parallel formation.
- 35 54. A bias fabric machine having thread carriers each comprising a tubular body portion, a delivery portion having a flat groove or recess through which the threads are delivered and positioned, and means for supporting a supply of threads.
- 40 55. A bias fabric machine having thread carriers each comprising a tubular body portion through which threads pass, a thread supply support portion, and a guide tip portion having a flat groove or recess for delivering a plurality of threads in flat parallel formation.
- 45 56. In a bias fabric machine, two frames, means for operating said frames in opposite directions simultaneously, one of said frames movable toward the other, and having two annular thread-carrier supports, said supports movable longitudinally with respect to the axis of oscillation and toward said other frame, means for moving said second frame toward said first frame and for moving said supports thereof at different speeds, a series of thread carriers for each frame, means for exchanging the series of thread carriers from each of said frames to the other after each oscillation.
- 50 57. A bias fabric machine having two thread-carrier frames, one movable toward the other, and having two annular thread-carrier supports movable at different speeds toward the other frame.
- 55 58. A bias fabric machine having two thread-carrier frames, one movable toward the other and having two thread-carrier supports movable at different speeds toward the other frame.
- 60 59. A bias fabric machine having two frames, one having a slotted annular thread-carrier positioning plate, and the other a slotted annular thread-carrier positioning plate and two annular thread-carrier supports, means for moving said second frame toward the other frame and for moving said supports toward said other frame at different speeds, thread-carriers positioned in alternate slots of the first named frame, means for supporting the same therein, thread-carriers positioned in alternate slots of the second frame, means carried by said annular thread-carrier supports for supporting said last named thread-carriers in the second frame, means for oscillating said frames simultaneously in opposite directions, and mechanism for actuating the thread-carrier supports to transfer the series of thread-carriers from each frame to the other frame after each oscillation.
- 65 60. In a bias fabric machine, two frames, means for operating said frames in opposite directions simultaneously, one of said frames movable toward the other, and having two annular thread-carrier supports, said supports movable longitudinally with respect to the axis of oscillation, and toward said other frame, means for moving said second frame toward said first frame and for moving said support thereof at different speeds, a series of thread carriers for each frame, means for exchanging the series of thread carriers from each of said frames to the other after each oscillation, and reversing mechanism for transferring carriers of one series to the other series when such carriers reach predetermined positions.
- 70 61. A bias fabric machine having two frames, one having a slotted annular thread-carrier positioning plate, and the other a slotted annular thread-carrier positioning plate and two annular thread-carrier supports, means for moving said second frame toward the other frame and for moving said supports toward said other frame at different speeds, thread-carriers positioned in al-

- ternate slots of the first named frame, means for supporting the same therein, thread-carriers positioned in alternate slots of the second frame, means carried by said annular
5 thread-carrier supports for supporting said last named thread-carriers in the second frame, means for oscillating said frames simultaneously in opposite directions, mechanism for actuating the thread-carrier sup-
10 ports to transfer the series of thread-carriers from each frame to the other frame

after each oscillation, and reversing mechanism for transferring carriers of one series to the other series when such carriers reach predetermined positions.

Signed at Los Angeles, California, this
16th day of February, 1918.
